ABSTRACT OF THE DISCLOSURE

An improved process of oil recovery comprising injecting into the formation through an injection well a hot fluid followed by injecting through the same well an oxygen-containing gas to establish a combustion front and driving the oil to a production well to recover the oil.

The present invention relates to a method of recovering hydrocarbons from an underground hydrocarbon-containing formation by thermal means. In such methods, heat is applied to the formation so as to reduce the viscosity of the hydrocarbon present in the pores of the formation to enable or improve the drainage of these hydrocarbons to the production wells through which it is lifted to the surface.

The heat required for the desired viscosity reduction of the hydrocarbon can be generated in situ by injecting oxygen-containing gas into the pores of the formation, which gas causes combustion of part of the hydrocarbon present within the formation. The water vapor generated during this reaction condenses against the cold parts of the formation, thereby forming a condensation front which heats the hydrocarbon and drives it towards the production wells. A drawback of this method is the high cost of compressing the oxygen-containing gas to a suitable pressure before injecting it into the formation.

In another thermal method, a hot fluid such as hot water, steam or another condensable gas is injected into the pores of the formation. The hot fluid heats the hydrocarbon through the pores of the formation to the production wells. In this method, the cost involved per unit of enthalpy supplied to the formation is less than the cost involved in the above-mentioned in situ combustion method. A drawback of this method, however, is the loss of heat to the part of the formation being treated, as well as the loss of heat to the cap rock and the base rock, which losses may become unacceptable near the end of the operation, in particular if there are great distances between the individual wells.

In accordance with the present invention these disadvantages of the known methods are reduced or eliminated, and a high recovery of hydrocarbons from a hydrocarbon-containing underground formation can be achieved at relatively low compression costs and with relatively low heat losses.

According to the invention the method of recovering hydrocarbons from an underground, hydrocarbon-containing formation comprises the following steps:

(1) arranging at least two wells penetrating into the formation and communicating with the pores of the formation,

(2) injecting via one of the wells into the pores of the formation a hot fluid comprising a liquid and/or a vapor capable of condensing in unheated parts of the formation under the conditions of operation, until a portion of the hydrocarbon has been displaced,

(3) after the cessation of such injection, injecting via the same well an oxygen-containing gas to create com-

2

bustion of hydrocarbon, and either simultaneously or alternately, a liquid to recover heat absorbed by the formation from the hot fluid, and

(4) recovering hydrocarbon through the other well during the sequence of the steps 2 and 3.

Preferably, the injection of the hot fluid in step 2 is stopped after at least 50% of the pore volume in the part of the formation to be treated has been heated by this fluid.

10 The steam or other hot fluid may be injected over the entire height of the hydrocarbon-containing formation or only at a particular level. In general, it will be preferred to inject the hot fluid at a level near the lowest part of the formation.

15 It is also preferred that the liquid in step 4 is injected at substantially atmospheric temperature.

If the water saturation in the pores of the lower layers of the hydrocarbon-containing formation is appreciably greater than the water saturation in the upper layers of

20 the formation, the injection of the treating fluids is preferably made into the layer or layers having the greatest water saturation, provided that this water saturation is lower than 100%.

The invention will now be described, by way of example, with reference to the accompanying drawing, in which FIGURES 1 and 2 show schematically a vertical section of part of the earth's crust including a hydrocarbon-containing formation, and injection and production wells. In this formation, the mobility of the hydrocarbon present in the pores is sufficiently low that it cannot be recovered in the most economic manner under influence of its own energy or by the aid of pumping equipment installed in the wells. The mobility is, furthermore, sufficiently low that the application of a cold fluid drive is not economically feasible. Such hydrocarbon has hitherto been economically recoverable, if at all, by a thermal method.

FIGURE 1 shows the injection of the hot fluid in step 2 of the method of the invention, whereas FIGURE 2 shows the injection of the oxygen-containing gas and the aqueous liquid in step 4 of the process.

From the surface 10 and through the layers 11 and 16 overlying the hydrocarbon-containing formation 12, there are drilled two wells 13 and 14, which penetrate into the formation 12. The wells are drilled and completed in a manner known per se, and for sake of simplicity all details such as casing, tubing, wellhead, cementing layers, liners, etc., are omitted from the drawing and description. One of the wells 13, is designed as an injection well for injecting the required agents for heating the contents of the formation 12. The other well, 14, is designed as a production well for recovering the hydrocarbons which are displaced from the formation. Although the formation 12 is shown in the drawing substantially horizontal, it will be understood that the method 45 of the invention may be applied with similar results to hydrocarbon-containing formations which are of the slanted type. The cap rock 16 which forms part of the overlying layers with 11 as well as the base rock 17, are substantially or entirely impermeable.

60 In accordance with the invention, there is first injected a hot fluid via injection well 13 into the pores of the formation, which fluid in this particular example consists of steam. This steam may be either wet, dry or superheated. If desired, a hydrocarbon may be mixed with the steam for increasing the recovery efficiency.

The injectivity of the steam into the formation 12 may be increased in the neighborhood of the well 13, by any of the known methods, e.g., by fracturing.

65 The steam is obtained from any convenient source (not shown), and must of course be at a pressure higher than the formation pore pressure, this steam is conducted

under this pressure into the top of the well 13. If desired, bleedwater from a boiler supplying the steam may also be injected into the well 13. This has the advantage that undesirable salts are removed from the boiler without loss of heat. Undesirable salts will be removed from the boiler if wet steam is employed for injection.

The injection of steam into the formation 12 is stopped after at least 50% of the pore volume of the part of the formation to be treated has been heated. This means in practice that the amount of injected steam is more than 3 to 10 times the pore volume measured as steam condensate. When the part of the formation to be treated is referred to there is to be understood that part of the formation arranged between the injection well(s) and the production well(s), which is, during the application of the method of the invention, sufficiently heated to allow the hydrocarbon to flow therefrom to the production well(s).

During injection of the steam, condensation occurs against the relatively cold hydrocarbon forming a condensation front 18 which, under the influence of further steam injection, travels in the direction of the production well 14. From here the hydrocarbon is recovered, if necessary with the aid of pumps or the like.

After the desired amount of steam has been injected into the pores of the formation 12, this injection is stopped, and in place thereof compressed air or other oxygen-containing gas is pumped into the pore space of the formation 12 where the temperature conditions enable spontaneous combustion to take place wherever the oxygen-containing gas comes into contact with sufficiently great amounts of hot hydrocarbon. In this way, as shown in FIGURE 2, a combustion front 19 is formed, which travels in the direction of the production well 14, and by virtue of vaporization and subsequent condensation of water already present in the formation and of water created by the combustion, forms a new condensation front 20.

An aqueous liquid is simultaneously or alternately with the oxygen-containing gas injected into the formation 40 through injection well 13, which liquid serves as a heat carrier for transporting the heat left behind in the formation by the preceding steam injection and by the combustion process. The liquid, suitably ordinary water, on contacting the hot formation, is heated and vaporized, thereby extracting heat from the formation and transferring it to colder parts of the formation, thereby also taking part in the formation of the new condensation front 20.

In the example as shown described with reference to 50 the drawing, the oxygen-containing gas is air, whereas the heat carrier is primarily water.

It will be clear from the above description that the present combination of the two processes which are known per se, namely a normal hot fluid drive and a 55 wet in situ combustion drive (in which air and water are simultaneously or alternately injected), constitutes very economic and efficient process for displacing hydrocarbon from the pores of hydrocarbon-containing underground formations. By first applying a steam drive to the formation, the advantage of low-energy requirements is obtained. This process is continued until the amount of heat absorbed by the treated part of the formation and adjacent layers rises to an undesirable value. At this point the manner of heat generation is changed from external heat generation by the injection of steam to in situ

heat generation by the injection of air. During the in situ combustion process, the heat which was previously absorbed in the treated part of the formation is transported by the water which is injected simultaneously or alternately with the air, towards the untreated part of the formation. In this manner, the reservoir of heat remaining from the steam drive phase is utilized to heat the injected water and thereby improve the overall efficiency. Furthermore, the increasing distance between the injection well and the condensation front, which would in a simple steam drive recovery unfavorably affect the heat transport by the steam in the later stages of the recovery, has little influence on the air passing therethrough in the second phase of the method of the invention. Since at the moment when the steam drive is replaced by the in situ combustion, the distance between the condensation front and the production well, and consequently also the injection pressure, are considerably smaller than the corresponding distance and injection pressure would be in a simple in situ combustion process, the economics of the method of the invention are likewise favorable.

Although in the example described with reference to the drawing only two wells have been shown for carrying out the method according to the invention, the present invention is by no means limited thereto. Any number of wells and any type of well pattern may be used.

I claim as my invention:

1. An improved method of recovering oil from an underground formation containing oil in substantially non-flowable state under formation conditions, comprising the following steps:

- (1) establishing injection and production wells which penetrate the oil production zone of the formation pores and are in communication with each other;
- (2) injecting through an injection well and into the production zone of the formation, steam until at least 50% of the pore volume of the formation has been steam heated and thereafter stopping the steam injection;
- (3) establishing a wet in situ combustion drive by injecting through the same injection well as in step (2) an oxygen-containing gas and alternately or simultaneously also injecting an aqueous liquid; and,
- (4) recovering the mobilized oil through a production well.

2. The method of claim 1 wherein the oxygen-containing gas is air and the aqueous liquid is water.

3. The method of claim 2 wherein in step (3) the injection of air and water is done simultaneously.

4. The method of claim 1 wherein in step (3) the water is injected after the in situ combustion front has been established.
